UNITED STATES PATENT OFFICE.

SAMUEL HAMILTON HOGGSON, OF CHICAGO, ILLINOIS.

TIME-STAMP.

SPECIFICATION forming part of Letters Patent No. 628,323, dated July 4, 1899.

Application filed August 17, 1898. Serial No. 688,805. (No model.)

To all whom it may concern:

Be it known that I, SAMUEL HAMILTON HOGGSON, a citizen of the United States, residing at Chicago, in the county of Cook and 5 State of Illinois, have invented new and useful Improvements in Time-Stamp, of which the following is a specification.

My invention relates to that class of hand-stamps known as "time-stamps"—i. e., 10 stamps for printing the time of their receipt or departure upon papers and articles of various kinds, and it contemplates the provision of a combined time-stamp and timepiece, the same being adapted by reason of its construction to stand upright upon an inking-pad or other rest without the time mechanism being affected thereby and being otherwise advantageous, as will be fully understood from the following description and claims when taken 15 in conjunction with the annexed drawings, in which—

Figure 1 is a front elevation of my improved time-stamp with some of the parts in section. Fig. 2 is a vertical section taken in a plane 20 at right angles to Fig. 1 with some of the parts in elevation. Fig. 3 is a horizontal section taken in the plane indicated by the line $\alpha\alpha$ of Fig. 1. Fig. 4 comprises disconnected perspective views of the main frame or body 25 and mount-plate of the stamp, and Fig. 5 is an enlarged inverted plan view of the printing-face of the stamp.

In the said drawings similar letters designate corresponding parts in all of the several 30 views, referring to which—

A designates the main frame or body of the stamp, which is preferably of the form shown and cast in one piece of aluminium or other suitable material. This frame or body comprises a casing a , an upright b , rising from 35 the casing and recessed, as indicated by c , and a knob d at the upper end of the upright, said knob being designed to serve as a handle to enable the operator to conveniently press the 40 printing-face of the stamp against the piece of paper or article to be stamped.

B designates a timepiece, which may be a 45 watch or clock, although I prefer to employ the former, as shown. This timepiece or watch 50 may be of the ordinary construction, with the exception that its casing is provided with a

flange e on its rear side designed to be sprung into the circular portion of the recess c , and its minute-shaft is extended, as indicated by f , and provided with a gear-wheel g , as shown, 55 for a purpose presently described. The said watch is securely held against casual displacement in the recess c of the body, but may be readily removed when desired, and when so removed the operator may, through 60 the medium of the wheel g , conveniently set its hands, if necessary.

C designates the printing-base of the stamp, which is preferably a cushion of rubber or other suitable material. This cushion C is 65 provided upon its face with two printing-dials h i , the one being designed to print the hours and the other the minutes. The hour-dial h is, for an important reason presently pointed out, provided with twenty-four graduations, the first twelve of which are numbered from "1" to "12" in consecutive order, as are the second twelve, with the number "1" of the second twelve next to the number "12" of the first twelve, as shown. Said dial h is 70 also provided with the conventional abbreviations "M.," "A. M.," and "P. M.," placed at proper points, as shown. The dial i is provided with sixty graduations, which are numbered in the manner shown or in any other 75 suitable manner.

The cushion C is further provided within the dials h i with circular recesses j k for a purpose presently described, while between the dials or at any other desired point it has 80 a rectangular recess l , this latter being designed to receive removable types m , n , and p for printing the names of the year and month, together with the day of the month.

D designates the mount-plate or plate in 85 which the rubber cushion C is mounted. This plate D is provided on its upper side with studs r , and on these studs and coincident studs s in the casing a of body A are mounted and secured by frictional contact or cement the yielding supports E , which are preferably of rubber and in the form of tubes, as 90 shown. These supports E connect the mount-plate and the casing and normally hold the body A above the mount-plate D and cushion 95 C , as shown. When, however, pressure is applied upon the upper end of the body A , 100

said supports E give and permit the body to move down with respect to the mount-plate and printing-cushion for a purpose which will be presently pointed out.

5 F G designate shafts which are journaled in and held against endwise movement in the casing a and which extend loosely through apertures t in the mount-plate and printing-cushion C into the recesses j k, respectively, 10 of said cushion, as shown. These shafts F G are provided at their lower ends with hands u v, respectively, which are formed of rubber or have rubber faces and are therefore adapted to print when they are properly inked and 15 pressed against the surface to be printed. The shaft F is also provided with a ratchet-wheel H having twenty-four teeth for a purpose presently described, while the shaft G is provided with a gear-wheel I, which meshes with a 20 gear-wheel J on a shaft K, as better shown in Fig. 3. Said shaft K extends through a bearing in the casing a of the body A into the recess c and is provided with a gear-wheel L in mesh with the gear-wheel g on the minute- 25 shaft of the watch, whereby it will be seen that the shaft G will make a complete rotation with each complete rotation of the minute-shaft of the watch and that consequently the hand v will move in concert with and at 30 a speed corresponding to that of the minute-hand of the watch and will always occupy a position with respect to the dial i corresponding to the position which the minute-hand of the watch occupies with respect to the dial thereof.

35 M designates a lever which is fulcrumed on an arbor w in the casing a and has a pawl x' at one end to engage the teeth of the ratchet-wheel H. N designates a cam which is fixed 40 on the shaft G, so as to engage the opposite end of the lever M, and is provided with an abrupt shoulder y, and P designates a spring which is connected to the lever M and casing a and has for its purpose to normally hold 45 the lever in engagement with the cam N and the pawl x' in engagement with the teeth of the ratchet-wheel H, as better shown in Fig. 3.

50 In the practice of the invention when the stamp is not in use it is designed and adapted 50 to stand in the upright position shown in Fig. 1 upon an inking-pad or other suitable base without the time mechanism being retarded in its movements or otherwise affected thereby. This is an important advantage, since 55 the device serves as an efficient and ornamental timepiece when not in use as a stamp, and it is due to the fact that the printing-hands u v normally rest in a plane above that of the printing-face of the cushion C and do 60 not contact with the base on which said cushion rests. The said printing-hands u v are also at all times connected with the mechanism of the watch and have no movement with respect to the same, and this, as will be readily 65 appreciated, contributes materially to the proper operation of the printing-hands and results in the hand v moving in concert with

and at a speed corresponding to that of the minute-hand of the watch and in the hand u being moved the distance of one tooth of wheel 70 H at the completion of each rotation of the hand v, such movement of the hand u being effected by the shaft G through the medium of the cam N, lever M, pawl x', wheel H, and shaft C. Consequently it will be observed 75 that when the face of the cushion C and the hands u v are properly inked by pressing them against an inking-pad or in any other suitable manner and the stamp is then placed upon and pressed against the paper or article 80 to be stamped the supports E will yield and permit the body A to move downward, with the result that the hands u v, as well as the face of the cushion C, will be pressed against the paper and the minute and hour, as well 85 as the day, month, and year, will be printed upon the paper or article. For instance, if the stamp is used at twenty-five minutes of two the impression on the paper or article stamped will show the minute-hand as pointing 90 to the number "35" and the hour-hand pointing to the number "1," indicating that the paper or article was stamped at "1.35," or twenty-five minutes of two.

95 As described in the foregoing, the hour-dial h has twenty-four graduations divided into two series, each of which has its graduations numbered in consecutive order, with the number "1" of each series arranged after the number "12" of the other series. This dial h is 100 highly advantageous for the reason that it permits the movement of the hour-hand to be continuous and obviates the necessity of any changing device to denote the "A. M.," "P. M.," and "M." divisions of the day of 105 twenty-four hours, as it is instantly apparent it is day if the point of the arrow is above an imaginary line drawn horizontally from "6 A. M." to "6 P. M." and night if below this line. It follows from that that all the 110 user of my improved stamp has to do is to change the type p once a day, the type n once a month, and the type m once a year and wind the watch at necessary intervals.

115 With all its advantages it will be observed that my improved time-stamp is very simple and compact and that it presents the appearance of a clock and serves to enhance, rather than detract from, the appearance of any desk upon which it is placed.

120 Having thus described my invention, what I claim is—

1. In a time-stamp, the combination of a printing-base, a body yieldingly supported above the base, a suitable time mechanism carried by said body, and a movable printing device connected with the time mechanism and normally resting in a plane above the face of the printing-base and movable with the body, whereby, when said body is depressed the printing device will be moved down to the plane of the face of the printing-base, substantially as specified.

125 2. In a time-stamp, the combination of a

printing-base, a suitable time mechanism, and a vertically-movable printing device connected and movable with the time mechanism and normally resting in a plane above the face of the printing-base; the said parts being so assembled that when the base is pressed against an article to be printed, the printing device will be caused to move downwardly to the same plane as the face of said base, substantially as specified.

3. In a time-stamp, the combination of a printing-base having a recess in its face and a dial surrounding said recess, a suitable time mechanism, yieldingly supported above the base, and a printing-hand connected and movable with the time mechanism and arranged in the recess of the printing-base and normally resting in a plane above the face of said base, substantially as specified.

20 4. In a time-stamp, the combination of a printing-base having a recess in its face and a dial surrounding said recess, a body yieldingly supported above the base, a time mechanism carried by said body, and a printing-hand connected and movable with the time mechanism and arranged in the recess of the printing-base and normally resting in a plane above the face of said base, substantially as specified.

25 5. In a time-stamp, the combination of a printing-base having two recesses in its face and also having a minute-dial surrounding one recess and an hour-dial surrounding the other, a body yieldingly supported above the base, a time mechanism carried by said body, a shaft carried by and movable with the body and extending into the recess within the minute-dial of the base and having a printing-hand at its lower end normally resting in a

30 plane above the face of the base, mechanism intermediate of said shaft and the minute-shaft of the time mechanism, a second shaft carried by and movable with the body and ex-

tending into the recess within the hour-dial of the base and having a printing-hand at its lower end normally resting in a plane above the face of the base, and mechanism intermediate of the first and last named shafts for moving the latter at intervals, substantially as specified.

50 6. In a time-stamp, the combination of a printing-base, a body yieldingly supported above the base and having the circular recess in its forward side, a timepiece having a casing adapted to be sprung into and thereby detachably secured in said recess and also having one of its shafts extended, and a movable printing device connected with the extended shaft of the timepiece and normally resting in a plane above the face of the printing-base and movable with the body, substantially as specified.

65 7. In a time-stamp, the combination of a printing-base having two recesses in its face and also having a minute-dial surrounding one recess and a continuous hour-dial of twenty-four graduations, a body yieldingly supported above the base, a time mechanism carried by said body, minute and hour shafts carried by and movable with the body and extending into the recess within the minute-dial and hour-dial, respectively, of the base and having printing-hands normally resting in planes above the face of the base, mechanism intermediate of the minute-shaft and the time mechanism, and mechanism intermediate of said minute-shaft and the hour-shaft for rotating the same step by step in one direction, substantially as specified.

70 8. In testimony whereof I have hereunto set my hand in presence of two subscribing witnesses.

SAMUEL HAMILTON HOGGSON.
